A. L. COFFEY

LIGHT REFLECTOR

Filed May 5, 1923

INVENTOR

Alfred L. Coffey

BY

Frank Warren

ATTORNEY

UNITED STATES PATENT OFFICE.

ALFRED L. COFFEY, OF SEATTLE, WASHINGTON.

LIGHT REFLECTOR.

Application filed May 5, 1923. Serial No. 636,975.

To all whom it may concern:

Be it known that I, ALFRED L. COFFEY, a citizen of the United States, residing at Seattle, in the county of King and State of Washington, have invented a certain new and useful Improvement in Light Reflectors, of which the following is a specification.

My invention relates to improvements in light reflectors and the object of my invention is to provide a light reflector of a form that is particularly adapted to intercept rays of light from an exterior source and reflect said rays of light outwardly in a direction parallel to their direction of approach and to further provide a light reflector that is capable of changing the color of all of the reflected rays of light.

Another object is to provide a light reflector having on its open front side a color screen, preferably of colored glass, and having a light reflecting surface that is made of two intersecting conic sections, namely a conical portion and a truncated portion formed and arranged so that their angle of intersection, measured in any plane that passes through their common axis, will be one hundred and fifty degrees whereby rays of light entering said reflector from an exterior source will always be reflected outwardly in a direction parallel to their direction of approach thereby producing a perfect and uniform color effect and preventing the formation of non-luminous or dead areas or circles in said reflector such as might occur if the reflecting surfaces were arranged at any other angle.

A further object is to provide a reflector that is particularly adapted to be used as a warning or danger signal, as on the rear ends of vehicles or in dangerous locations along streets, highways, railroads, shore lines and the like.

I accomplish these objects by devices illustrated in the accompanying drawings, wherein—

Figure 1 is a somewhat diagrammatic view in longitudinal mid-section of a reflector constructed in accordance with my invention;

Fig. 2 is a view in elevation on a reduced scale showing the color screen or glass forming the front portion of my reflector; and

Fig. 3 is a view on a reduced scale looking into the open end of my reflector with the color screen removed.

Referring to the drawings throughout which like reference numerals indicate like parts, I have shown a light reflector formed of a conical portion 4 and a truncated portion 5 arranged about a common axis A, A and intersecting each other in a plane B, B at right angles to the axis A, A, the conical portion 4 and truncated portion 5 being fixed relative to each other.

The angle of divergence of the reflecting surface of the conical portion 4 measured in an axial plane is 120 degrees and the angle between the respective reflecting surfaces of the conical portion 4 and the truncated portion 5 measured in an axial plane is 150 degrees thus forming an angle of 90 degrees between the reflecting surface of the conical portion 4 and the diametrically opposite reflecting surface of the truncated portion 5.

Mounted at the front or open end of the truncated portion 5 is a co-axially arranged color screen preferably formed of an annular plate 6 of colored glass and a central disc 7 of white or noncolored glass, the diameter of the disc 7 being equal to the maximum diameter of the conical reflector portion 4 and the annular plate 6 having a minimum or internal diameter equal to the minimum diameter of the truncated portion 5 and external diameter equal to or greater than the maximum diameter of said truncated portion 5, the result of this arrangement being that rays of light traveling toward or away from the truncated portion 5 in directions parallel with the axis A, A will pass through the colored annular plate 6 and similar rays moving toward or away from the conical portion 4 parallel with the axis A, A will always pass through the clear central disc 7.

If desired the central disc 7 may be colored glass and the annular front screen may be formed of colored glass and the same color effect produced or the entire front screen may be formed of colored glass.

The length of the truncated portion 5 measured from front to rear along the reflecting surface in any radial plane is the distance between the points where said truncated surface would be intersected by two straight lines drawn at an angle of 60 degrees from the extremities of a diametrically opposite portion of the conical reflecting surface 4. In practice the length of the reflecting surface of the truncated portion 5 is

equal to the diameter of the smaller end of said truncated portion 5 measured on the plane B, B or to one half of the diameter of the larger end of said truncated portion 5 measured on the plane of the color screens 5 and 6. The length of the reflecting surface of the truncated portion is an important factor and must be determined as above described to secure a maximum efficiency and 10 prevent a wrong reflection of light rays.

The operation of my light reflector is as follows: Rays of light from external sources entering the reflector in directions substantially parallel to the axis A, A and incident 15 on the truncated reflecting surface 5 at an angle of 30 degrees will be refracted at an angle of 30 degrees, and will strike the conical reflecting surface 4 at a diametrically opposite point at an angle of 60 degrees and 20 be refracted therefrom at an angle of 60 degrees in a direction parallel to their direction of approach and parallel to the axis A, A; and, conversely rays of light entering in directions parallel to the axis A, A and 25 incident at an angle of 60 degrees on the conical reflector 4 will be refracted therefrom at an angle of 60 degrees and will strike the truncated reflecting surface 5 at a diametrically opposite point at an angle of 30 degrees from which they will be refracted 30 at an angle of 30 degrees in a direction parallel with their direction of approach and parallel with the axis A, A.

From the preceding description together 35 with the accompanying drawings, in which paths along which the light rays may travel are indicated by broken lines, it will be seen that light rays entering through the annular glass 6 will always be reflected out 40 through the disc 7 in lines parallel to their direction of approach and that light rays entering through the glass disc 7 will always be reflected outwardly through the annular glass 6 in directions parallel to their direction of approach, the light rays always passing 45 through the colored screen either on entering or leaving the reflector and thereby being caused to take on the color of such screen, it being understood that, if desired, 50 the central disc 7 may be colored and the annular plate 6 may be non-colored.

The reflector surfaces 4 and 5 may be formed of any material adapted for that

purpose and may be mounted in any well known manner.

The two reflecting surfaces 5 and 4 being arranged so that they intersect each other at an angle of 150 degrees as hereinbefore described serve to reflect the rays of light out evenly and in a direction parallel to the direction of approach of said light rays thereby producing a uniform color effect and eliminating the dark or non-illuminated areas or rings such as are frequently observed in connection with other reflectors.

The foregoing description and accompanying drawings clearly disclose what I now consider to be a preferred embodiment of my invention but it will be understood that this disclosure is merely illustrative and that such changes in the reflector may be made as are within the spirit of the invention.

What I claim is:

1. A reflector embodying a conical portion having a concave light reflecting surface forming an angle of 60 degrees with respect to its axis and a portion of truncated shape disposed in axial alignment with said conical portion and having reflecting surfaces forming an angle of 30 degrees with respect to said axis and intersecting the reflecting surfaces of said conical portion at an angle of 150 degrees.

2. A light reflector embodying a concave conical reflecting surface, a reflecting surface of truncated cone shape coaxial with said conical reflecting surface and intersecting the same at an angle of 150 degrees and a colored light screen extending across the open front end of said light reflector.

3. A light reflector embodying a concave conical reflecting surface, a reflecting surface of truncated cone shape coaxial with said conical reflecting surface and intersecting the same at an angle of 150 degrees, and a light screen extending across the open front end of said light reflector and having a colored portion in front of one of said reflecting surfaces and a non-colored portion in front of the other of said reflecting surfaces.

In witness whereof, I hereunto subscribe my name this 25th day of April, A. D. 1923.

ALFRED L. COFFEY.
